UNITED STATES PATENT OFFICE.

EDWARD S. LEA, OF TRENTON, NEW JERSEY, ASSIGNOR TO ULYSSES GRANT KING, OF TRENTON, NEW JERSEY.

TUBE-CUTTING MACHINE.

1,421,263.

Specification of Letters Patent. Patented June 27, 1922.

Application filed April 30, 1921. Serial No. 465,820.

To all whom it may concern:

Be it known that I, EDWARD S. LEA, a citizen of the United States, residing in Trenton, New Jersey, have invented a Tube-
5 Cutting Machine, of which the following is a specification.

My invention relates to the manufacture of copper ferrules of the type employed, among other things, for securing the tubes 10 of boilers to the tube sheets, the object of my invention being to provide a machine for cutting copper tubing into lengths suitable for this purpose.

Heretofore it has been the custom in 15 making copper ferrules to press them up by means of suitable dies out of sheet copper, and it has been found impracticable to employ tubing in the manufacture of these articles due to the fact that no practicable 20 machine has been available capable of satisfactorily cutting the sections from the copper tubing.

A machine capable of successfully performing this work I hereinafter describe 25 and illustrate in the accompanying drawings, in which:

Figure 1, is a plan view of the machine;

Fig. 2, is a side elevation;

Fig. 3, is a dissociated plan view of the 30 cutting head of the machine;

Fig. 4 is a front elevation of the cutting head;

Fig. 5 is a dissociated plan view of the feeding mechanism.

35 Figure 6 is a side elevation of the feeding mechanism, and

Fig. 7, is a section on the line 7-7, Fig. 6.

With reference to the drawings, the 40 machine comprises in its present form a suitable base or pedestal 1 having mounted thereon in suitable bearings 2, four horizontally disposed and parallel shafts 3, 4, 5 and 6. The said shaft 3 carries at its outer end, in 45 the present instance, a pulley 7 by means of which the shaft may be connected to any suitable source of power (not shown), while on the inner end of the shaft 3 is a gear pinion 8 which intermeshes with a gear wheel 9 upon the shaft 5. The shaft 5 carries also a pinion 10 which meshes with a gear 11 upon the shaft 4, and a second pinion 12 which meshes with a gear 13 upon the shaft 6. By means of these gear trains the 50 shafts 4, 5 and 6, are all operatively con-

nected together and with the shaft 3 through which the motive power of the machine is applied.

Carried on the forward end of the shaft 6 is a rotary cutter disk 14, said disk being 60 shaped as shown in Figs. 3 and 4, and being substantially circular in form, with a flange or peripheral extension 15 at the inner edge thereof which extends around substantially two-thirds of the circumference of 65 the disk.

Upon the forward end of the shaft 5 is a cutting head or mandrel 16, the forward face of which is adapted normally to lie substantially in the same plane as the rear- 70 ward face of the cutting disk 14, as shown in Fig. 3, said head 16 being so disposed laterally of the disk 14 that while the said flange 15 of the disk 14 will overlap the face of the mandrel 16, the unflanged portion 14^a 75 of the disk 14 will not overlap the face of the head but will lie outwardly of the periphery of the said head, in the manner shown in Figs. 3 and 4. The diameter of the mandrel 16 is increased at the outer end 80 to form a head 16^a, the periphery of which is knurled as shown in Fig. 3.

A supporting disk 17 is rotatably mounted upon a bracket 18 carried by the base 1, and is disposed slightly in advance of the forward face of and below the said mandrel 16 and on the opposite side of said mandrel from the cutting disk 14. The said bracket 18 in the present instance is pivotally 85 mounted at the bottom and has a circumferential slot 19 therein through which extends a bolt 20 by means of which the said bracket is held in any desired fixed position, said slot with the pivotal mounting of the bracket providing means for adjusting the 90 supporting disk 17 toward and away from the said head 16.

The shaft 5 is movable axially in its bearings, and means is provided for intermittently reciprocating the said shaft rearwardly in its bearings at predetermined intervals, said shifting means comprising an arm 21 oscillatory upon a vertically disposed pivot 21^a upon the base 1, said arm having its free end disposed within the circumferential groove 22 of a cam 23 mounted upon the shaft 4. The arm 21 is also disposed intermediate its ends between two suitably placed collars or extensions 24, 24, upon the shaft 5, and it will be apparent 110

- that as the shaft 4 rotates carrying with it the cam 23, the shaft 5 will be given an intermittent reciprocatory movement rearwardly from the normal position in which it is indicated in the drawings. In the present instance, the collars 24 upon the shaft 5 consist of a pair of ball bearing races 25, 25, which are held in place against the opposite sides of the arm 21 by means of nuts 26, 26.
- 10 As clearly shown in Fig. 1, the pinions 8 and 12 and the gear wheel 11 are made sufficiently wide to accommodate this axial movement of the shaft 5, while retaining the interconnection between the respective shafts.
- 15 Extending forwardly from the bearing 2 at the forward end of the shaft 5, is a cylindrical sleeve 27 into which the said head 16 is adapted to move when the shaft 5 is shifted rearwardly in the manner described,
- 20 said sleeve 27 having a series of radial openings extending therethrough, in each of which is disposed a plunger 28, said plungers being retained normally with their inner ends resting against the surface of the mandrel 16, by means of an endless spiral spring 29 extending completely around the periphery of the sleeve 27 and bearing against the outer ends of the said plungers 28, which are suitably recessed to form sockets for the reception and retention of the spring. It will be noted that as the shaft 5 is shifted rearwardly and the mandrel 16 is drawn into the sleeve 27, the head 16^a of the mandrel is permitted to pass by reason of the free outward movement of the said plungers 28, which latter at the same time are retained in contact with the surface of the said head.
- 30 The operation of the mechanism thus far described is as follows:
- 40 A tube is fed forward so that the end of the tubing passes onto the mandrel 16, the end edge thereof abutting the sides of the plungers 28, this passage of the tube over the head being possible when the unflanged portion 14^a of the disk 14 is in the position shown in the drawings. As the parts continue to revolve, the flange 15 of the disk 14 is brought into contact with the side of the tubing, and first forces it laterally against the knurled surface of the head 16, insuring thereby the rotation of the tubing with the mandrel, and thereafter in conjunction with the said mandrel 16, shears a portion of the tubing from the body thereof, the disk 17 acting to properly support the end of the tube during and after the shearing operation.
- 50 Immediately following the completion of the shearing, the mandrel 16 is withdrawn
- 60 into the sleeve 27, in the manner previously described, the plungers 28 functioning as wipers to prevent the entrance into the said sleeve 27 of the severed portion of the tubing, which latter portion, when the head 16
- 65 has been completely withdrawn, is permitted

to fall downwardly into a suitable receptacle placed below the cutting head.

For supporting the tube in the proper feeding position and for feeding the tube at the proper intervals forwardly onto the mandrel 16, I provide the following mechanism: Extending forwardly from the base member 1 and between the said base 1 and a second base member 30, is a pair of spaced angle irons 31, 31, said angle irons being substantially parallel to the shafts 3, 4, 5 and 6, and each having a web 31^a disposed vertically to constitute tracks for a carriage 32, which carriage has at one side a pair of wheels 33, 33, grooved to fit the edge of the said webs 31^a, and having at the opposite side a suitable wheel or roller 34 which is adapted to travel upon the said web 31^a of the oposite angle iron 31. Also extending between the bases 1 and 30 and overlying the said carriage 32 is a rack 35, the teeth or notches of which are on the under side, as shown in Figs. 2 and 6, and secured to the carriage 32, and extending upwardly therefrom at one side of the rack 35 is a bracket 36 which carries at the top a spindle 37, upon which is a grooved wheel 38 overlying and adapted to travel along the upper edge of the said rack 35. Extending laterally from the said bracket 36 is a horizontally disposed bearing sleeve 40, in which sleeve is journaled a shaft 41, having at the outer end thereof an operating arm or lever 42, and on the inner end a disk 43, from which extends an eccentrically disposed pin 44, which occupies a suitable recess or aperture in a pawl 46, said pawl being supported entirely upon the said pin 44, and having its forward end adapted to engage the teeth of the rack 35, in engagement with which teeth the said forward end is retained by means of a suitable counterweight 47, which is carried by a rearward extension 46^a of the said pawl.

Pivots secured to the said bracket at 50 is a second detent 51, which extends in the opposite direction from the detent 46, the outer end of the said detent 51 being adapted to engage the teeth of the rack, and said outer end being retained in engagement with said teeth by means of a spring 52 which is connected to the top of the bracket 36 and to the outer end of the detent. Means is also provided for maintaining a constant rearward tension upon the carriage, said means consisting in the present instance of a cord 120 75 secured to the carriage and to which a counterweight (not shown) is attached.

From the foregoing description it will be apparent that oscillation of the operating lever 42 first rearwardly and then forwardly 125 will effect the shifting of the carriage to the extent of one or more teeth of the rack 35, the amount of the forward feeding of the carriage being controlled by means of a pin 53 extending downwardly from the lever 130

disk 42^a, and adapted to engage a suitable lug or stop 54 when the operating lever 42 is oscillated to the full desired extent.

Also mounted upon the carriage is a chuck 60 for holding the tubing, said chuck being connected by means of a universal joint 61 to a spindle 62 rotatably mounted in a suitable bearing 63 on the said carriage, said bearing 63 being carried in the present instance upon a suitable slide 64 mounted in vertically disposed slideways 65 in a second slide 66 mounted in turn in suitable horizontally disposed slideways 67 in a depending bracket 68 upon the said carriage. A screw 15 69 is attached to the slide 64 at the bottom thereof and extends through a threaded lug 70 on the slide 66, and a suitable operating wheel or handle 71 is attached to the said screw whereby the slide 64 may be shifted 20 vertically in the said slideways 65. Suitable screw feeding means 72 is also provided upon the slide 66 for feeding this latter slide horizontally in its slideways 67. By this means both a vertical and horizontal adjustment 25 of the chuck 60 and the bearing 63 is provided for. The universal joint 61 accommodates the irregular movement of the end of the tube at the cutting head, while the adjustments of the bearing 63 provide for 30 changing the alignment of the tubes in accordance with their diameters.

In operating the machine, the operator standing with his hand upon the lever 42 feeds forwardly at the proper moments the 35 tubing held in the chuck by manipulation of the said lever in the manner specified, the tubing being fed onto the mandrel each time that the unflanged portion 14^a of the disk 14 lies opposite thereto.

40 I preferably make the rack 35 detachable from its supporting members 35^a and 35^b, to which in the present instance it is attached by means of bolts 35^c, so that one rack may be replaced by others in which the teeth have 45 a different pitch, thus providing feeding means for ferrules of any desired length.

I claim:

1. In a tube cutting machine, the combination with internal and external shearing elements, of mechanism for freeing the internal element of the severed portion of a tube operated upon to permit the feeding thereto of the uncut portion of the tube.

55 2. In a tube cutting machine, the combination with internal and external shearing elements, of mechanism for feeding a tube intermittently to the said elements, and mechanism for freeing the internal element of the severed portions to permit the feeding thereto of the uncut portion of the tube.

60 3. In a tube cutting machine, the combination with a rotary element adapted to enter the interior of the tube through an end thereof, of a second rotary element the axis 65 of which is fixed relative to the axis of the

said inner element, said outer element having a peripheral recess providing a space between the periphery of the inner element and the periphery of the outer element at said recess permitting the passing of the tube 70 over the said inner element.

4. In a tube cutting machine, the combination with an element adapted to enter the tube through an end thereof, of a second element relatively fixed with respect to the 75 first and adapted to operate against the outer face of said tube and together with the said inner element to shear the tube, and means for interrupting the operation of said outer element to permit the passing of the tube 80 over the said inner element.

5. In a tube cutting machine, the combination with a rotary element adapted to enter the tube through an end thereof, of a continuously rotated element whose axis is 85 relatively fixed with respect to that of the said rotary element adapted to operate upon the outer surface of said tube and in conjunction with the said inner element to shear the tube, and means for interrupting the shearing 90 action of said elements to permit the passage of the tube over the said inner element.

6. In a tube cutting machine, the combination with a supporting element adapted 95 to enter the interior of the tube through an end thereof, of a shearing element adapted to operate upon the outer surface of the tube and in conjunction with said support to shear the said tube, and mechanism for 100 shifting said supporting element away from the severed portion of the tube to release said severed portion.

7. In a tube cutting machine, the combination of a pair of continuously rotating 105 shearing elements, one of which is adapted to enter the interior of the tube and the other to operate upon the exterior of the tube, and means for interrupting the shearing action of said elements to permit the passage of the 110 tube over the said inner element.

8. In a tube cutting machine, the combination of a pair of continuously rotating shearing elements, one of which elements is adapted to enter the interior of the tube through the end thereof and the other of said elements to operate upon the exterior of said tube, means for interrupting the shearing action of said elements to permit the passage of the tube over the said inner element, and mechanism operable after the severing of each section from the tube for withdrawing said inner element to release the said severed portion of the tube.

9. In a tube cutting machine, the combination of a pair of rotary shearing elements, one of which is adapted to enter the interior of the tube and the other of which is adapted to operate upon the exterior of the tube, of means for intermittently feeding the 130

tube onto the said inner element, and mechanism for intermittently withdrawing the said inner element to release the severed sections of the tube.

- 5 10. In a tube cutting machine, the combination of a rotating element adapted to enter the interior of the tube through one end, a second rotating element adapted to operate upon the outside of said tube and in 10 conjunction with the said inner element to sever a portion of the tube, a member adapted to grip the other end of the tube, a member rotatably mounted substantially in alignment with said inner element, and a universal connection between the said rotatable 15 member and the tube gripping member.

11. In a tube cutting machine, the combination of a rotating element adapted to enter the tube through one end thereof, a 20 second rotating element adapted to operate against the outer surface of said tube and in connection with said first member to sever a portion of the tube, a member adapted to grip the other end of said tube, a member 25 rotatably mounted substantially in alignment with said first named rotating member, a universal connection between the tube gripping means and the rotatably mounted member, and means for adjusting the said 30 latter member to different positions relative to the said first named rotating element.

12. In a tube cutting machine, the combination with a rotating element adapted to enter the interior of a tube through one end 35 thereof, a second rotating element adapted to operate against the outside of said tube and in conjunction with said first element to sever a portion therefrom, a carriage movable toward and away from first element 40 and substantially axially thereof, rotatable means carried by said carriage for gripping the other end of said tube, and means for intermittently advancing the said carriage toward the said first named element in pre- 45 determined steps.

13. In a tube cutting machine, the combination of a rotating element adapted to enter a tube through one end thereof, a second rotating element adapted to operate 50 against the outside of said tube and in conjunction with said inner element to sever a portion therefrom, a carriage movable toward and from said first element and substantially axially thereto, means upon the 55 said carriage for rotatably supporting the outer end of said tube, a relatively fixed rack, a pawl carried by the carriage and adapted to engage the teeth of said rack,

and means for shifting said pawl a predetermined amount to effect the movement of 60 said carriage toward the severing elements.

14. In a tube cutting machine, the combination of a rotating element adapted to enter a tube through one end thereof, a second rotating element adapted to operate 65 against the exterior of said tube and in conjunction with said first element to sever portions therefrom, a fixed sleeve mounted rearwardly of said first element, means for withdrawing said element into said sleeve, 70 and means for preventing the withdrawal of the severed portions of the tube into the sleeve with the said element.

15. In a tube cutting machine, the combination with a rotating element adapted to 75 enter a tube through one end thereof, a second rotating element adapted to operate upon the exterior of the tube and in conjunction with said first element to sever portions therefrom, a fixed sleeve mounted 80 rearwardly of said first element, means for withdrawing said element into the sleeve, and elements carried by said sleeve and adapted to bear against the periphery of 85 said element as it is withdrawn into the sleeve, substantially for the purpose set forth.

16. In a tube cutting machine, the combination with a rotating element adapted to enter a tube through one end thereof, a 90 second rotating element adapted to operate upon the outer surface of said tube and in conjunction with said first element to sever portions therefrom, a sleeve mounted rearwardly of said first element, means for withdrawing said element into the sleeve, elements movably mounted in said sleeve and disposed radially of said rotating element, and resilient means tending to retain the inner ends of said radially disposed elements 95 100 in contact with the surface of said rotating element.

17. In a tube cutting machine, the combination of a rotating element adapted to enter the interior of a tube through one end 105 thereof, a second rotating element adapted to bear against the outside of said tube first to force the said tube tightly against the inner element whereby said tube is rotated with said element and thereafter to operate 110 in conjunction with the said inner element to shear a portion of the tube, and means for rotatably and flexibly supporting the outer end of said tube.

EDWARD S. LEA.
